UNITED STATES PATENT OFFICE

WILLIAM H. CONKLE, OF PHOENIX CITY, ALABAMA

FEELER MECHANISM FOR MAGAZINE LOOMS

Application filed April 12, 1928. Serial No. 269,547.

This invention relates to feeler mechanisms for magazine looms of that type embodying a slide member, feelers pivotally mounted on the slide member, a transmitter slidably independently of the slide member and connected to the feelers and associated with the means for controlling the operation of the bobbin replenishing mechanism of the loom.

The present invention has for one of its objects to improve and simplify feeler mechanisms of the kind stated to the end that their cost of manufacture may be reduced to the minimum, to the end that they will be more positive and effective in operation, and to the end that the present loss of yarn will be avoided.

The foregoing and other objects are attained by the construction, combination and arrangement of parts hereinafter fully described and claimed, and illustrated in the accompanying drawings, wherein:

Figure 1 is a top plan view of the feeler mechanism shown in contact with a full bobbin and associated with means for controlling the bobbin replenishing mechanism of a loom,

Figure 2 is a sectional view taken on the vertical plane indicated by the line 2—2 of Figure 1,

Figure 3 is a view in front elevation of the bobbin, feeler mechanism and control finger of the means for controlling the bobbin replenishing mechanism,

Figure 4 is a view on an enlarged scale taken on the horizontal plane indicated by the line 4—4 of Figure 2,

Figure 5 is a sectional view taken on the vertical planes indicated by the line 5—5 of Figure 4,

Figure 6 is a similar view taken on the vertical plane indicated by the line 6—6 of Figure 4, and

Figure 7 is a sectional view taken on the vertical planes indicated by the line 7—7 of Figure 4.

Referring in detail to the drawings, 1 designates a portion of the bobbin magazine of a Crompton and Knowles loom. An angular arm 2 is carried by the part 1, and a vertical plunger 3 reciprocates therein. An actuating lever 4 is pivoted between its ends, as at 5, to

the plunger 3, and it rises and falls with the plunger during the normal operation of the loom. One end of the lever 4 extends in a slot 6 and across a hole 7 formed in the arm 2. The other end of the lever 4 is connected with a rod 8 which extends upwardly to the replenishing mechanism of the loom.

A shaft 9 is rotatably supported by spaced bearings 10 and 11 extending forwardly from the stand 1. A finger 12 is secured to the shaft 9 and is pivotally connected to a controller pin 13 which extends through the hole 17 in the arm 2 and is normally under the actuating lever 4. A collar 14 secured to the shaft 9 receives one end of a coil spring 15, and the other end of the spring is received by a bearing 11. A second finger 16 is secured to the shaft 9 and extends upwardly therefrom for engagement with the slide member of a feeler mechanism to be hereinafter described.

When the finger 16 is rocked forwardly into the position shown in Figure 2, the controller pin 13 will be withdrawn from under the actuating lever 4, with the result that the lever may descend without causing movement of the rod 8. When, however, the finger 16 is not moved into this position, the controller pin 13 remains under the actuating lever 4, with the result that when the lever descends the rod 8 is depressed and the bobbin replenishing mechanism is operated. The structure thus far described and constituting the means for controlling the bobbin replenishing mechanism of the loom, is substantially the same as that set forth in Patent No. 1,030,748.

The feeler mechanism comprises a bracket 17 which is pivotally mounted, as at 18, upon the part 1 and which is yieldingly held in proper position by a coil spring 19. The bracket 17 is provided in its upper side with a recess 20 for the reception of a slide member 21, a feeler 22 and springs 23 and 24. These parts are held within the recess 20 by a plate 25 secured in place by screws 26. The slide member 21 contacts with one side wall of the recess 20 and extends through an opening 27 in the front end of the bracket 17. The slide member 21 is held against lateral movement by said side wall of the recess 20, by the walls of the

opening 27 and by a lug 28 located in the recess and extending forwardly from the rear end of the bracket 17. The spring 23 is positioned between the front wall of the recess 20 and a lug 29 projecting laterally from the slide member 21, and it yieldingly maintains the slide member in its normal rearmost position. This position of the slide member 21 may be varied by a set screw 30 carried by the rear end of the bracket 17 and extending into the recess 20 in alignment with the slide member. The set screw 30 is maintained in adjusted position by a lock nut 31. The feeler 22 passes through a horizontal slot 32 in the rear end of the bracket 17, and it is provided with an angular front end 33 and an arcuate rear end 34. The front end 33 of the feeler 22 is pivotally connected, as at 35, to the slide member 21, and the rear end 34 thereof has a portion of its convex side provided with teeth 36. The feeler 22 is connected to the slide member 21 for movement laterally with respect thereto and in the plane thereof, and it is normally held at a slight inclination to the slide member 21 and against the inclined side 28^a of the lug 28 by the spring 24. This spring is provided with a coil 37 which is mounted on a vertical stud 38 extending upwardly from the bottom wall of the recess 20, and it is provided with an arm 39 which contacts with the feeler 22 and with an arm 40 which contacts with one side wall of the recess.

In practice, the slide member 21 and the feeler 22 are yieldingly held in their normal positions by the springs 23 and 24, respectively, and when in these positions the slide member is arranged at right angles and the feeler at an acute angle to the longitudinal axis of the bobbin. When the feeler 22 is engaged by a bobbin containing yarn, it will be restrained against angular movement with respect to the slide member 21 by reason of the engagement of its teeth 36 with the yarn. Due to the fact that the feeler 22 is held against angular movement with respect to the sliding member 21, the control finger 16 will be moved into the position shown in Figures 1 and 2, with the result that the controller pin 13 will move from under the actuating lever 4. When, however, the yarn on the bobbin has become exhausted, the feeler 22 will not be held against angular movement with respect to the sliding member 21 but will slide along the bare barrel of the bobbin and permit the rearward movement of the control finger 16 and the controller pin 13 by the spring 15. The controller pin 13 is now under the actuating lever 4, with the result that when the lever descends the rod 8 is depressed and the bobbin replenishing mechanism is operated.

As the bracket 17 is pivotally mounted and as it is yieldingly maintained in place by the spring 19, the feeler cannot become broken

as the result of a bobbin hanging in the shuttle or from any other cause.

It should be understood that the drawings are merely illustrative and do not pretend to give exact proportions. Furthermore, the said drawings are illustrative of a preferred construction, it being my expectation that various changes and modifications may be made without departing from the spirit and scope of my invention.

What is claimed is:—

In a feeler mechanism for looms, a bracket having a hollow section, a slide member carried by the section at one side thereof, said section having a portion abutted by said slide member, said slide member being of substantially the length of the section and extending forwardly beyond the same, the section having a shoulder adjacent the slide and the latter having a lug, an expansive spring arranged in the hollow portion and engaging said lug and shoulder, a feeler pivoted to the slide member within the bracket and extending rearwardly beyond the bracket, and being adapted to move angularly with respect to the slide member when the yarn on the bobbin becomes exhausted, means yieldingly holding the feeler against angular movement with respect to the slide member, a lug integral with said section extending inwardly from the rear wall thereof and being in contact with the rear portion of the slide, said feeler being in contact with the last mentioned lug, and means for operating the slide member and adapted to operate the replenishing mechanism of the loom when the feeler moves angularly with respect to the slide member.

In testimony whereof I affix my signature.

WILLIAM H. CONKLE.
